[57] CLAIM

The ornamental design for the word formation game, as shown and described.

DESCRIPTION

FIG. 1 is a front view of a game rack, part of word formation game, shown separately for ease of illustration;

FIG. 2 is a top view of FIG. 1.

FIG. 3 is a front view of a game rack with the game pieces installed on the game piece shafts.

FIG. 4 is a top view of a game base, showing the base, game rack dividers and hinged sides in the opened position.

FIG. 5 is a side view of FIG. 4.

FIG. 6 is a top view of my new design for a word formation game showing the base of FIG. 4 with the hinged sides closed and the assembled game racks of FIG. 3 installed; and,

FIG. 7 is a side view of FIG. 3.
